UNITED STATES PATENT OFFICE.

ELMER M. JONES, OF ATLANTA, GEORGIA.

AUTOMATIC SIGNALING AND TRAIN-STOPPING DEVICE.

1,126,778.

Specification of Letters Patent.

Patented Feb. 2, 1915.

Application filed May 13, 1910. Serial No. 561,067.

To all whom it may concern:

Be it known that I, ELMER M. JONES, a citizen of the United States, residing at Atlanta, in the county of Fulton and State 5 of Georgia, have invented a certain new and useful Improvement in Automatic Signaling and Train-Stopping Devices, of which the following is a full, clear, and exact description, reference being had to the accompanying 10 drawings.

My invention relates generally to railway signaling devices and more particularly relates to automatic stop signals of the semaphore type.

15 In general it may be said that in the signalling device here disclosed, the semaphore is adapted to show under normal conditions a danger signal, which will be changed to indicate clear when the train reaches a position 20 a predetermined distance away from the signal or tower, provided that the track ahead is clear and that the usual track circuits for setting in operation the semaphore signal are in working order.

25 The device further comprises mechanism which will ordinarily project into the path of travel of a lever or other actuator on the locomotive, which actuator may operate a signal in the cab, or the actuator may be 30 operatively connected with a valve in the air line of the train. This actuator upon the locomotive will be moved by its engagement with the mechanism which projects in its path and accomplish its intended function, 35 unless the train has not been stopped before passing the signal tower.

Generally speaking, the invention comprises the elements and combinations thereof set forth in the accompanying claims and 40 explained in the description, by reference to a preferred embodiment as an example.

Reference should be had to the accompanying drawings forming a part of this specification, in which—

45 Figure 1 represents, in a more or less diagrammatic manner, a signal tower with a semaphore located at the top thereof and also illustrates the manner of engagement between the signal-actuator on the locomotive and the arm which normally stands in its path of travel; Fig. 2 is a side elevation 50 of the mechanism which operates the signal

arm or semaphore of the tower, this mechanism being shown in position to operate the semaphore to show a clear track; Fig. 3 is a 55 side elevation of the mechanism shown in Fig. 2 in its normal position—that is, the position where the arm is at danger; Fig. 4 is a front elevation or edge view of the operating mechanism, showing also the arm 60 which projects into the path of travel of the actuator upon the locomotive; Fig. 5 is a detail of the electric switch; and Fig. 6 is a vertical section of the cushioning device for the semaphore operating rod. 65

The mechanism here shown and described is intended for use in connection with a track circuit which normally, when the track ahead is clear, maintains a relay 1 de-energized. When the train comes within a 70 predetermined distance of the signal tower, the relay 1 will remain deenergized in the event that the track conditions ahead are not clear; but, on the contrary, if the track conditions are proper for the further progress 75 of the train, the relay becomes energized to operate the mechanism for setting the semaphore to show a clear track and to move the arm which the locomotive might operate into a position to permit the locomotive to 80 pass without operating the same.

The frame of the operating mechanism shown includes an L-shaped bracket or plate 2 having a back portion 2^a and an extending shelf 2^b. Near the upper part of the back 85 2^a the arm 3^a of a second L-shaped bracket 3 is secured. An arm 3^b of the latter bracket depends for a certain distance in a direction parallel with the portion 2^a of the bracket 2.

A shaft 4 is journaled at one of its ends in 90 the depending arm 3^b referred to, and at its opposite end is mounted upon the portion 2^b of the bracket 2. Upon the shaft 4 is mounted a wheel 5, the periphery of which is provided with a groove. Surrounding 95 the wheel, and within the groove, is a sprocket chain 6. This chain, while retained against lateral displacement, by the walls of the groove, is not affixed to the wheel in any manner, so that while ordinarily the wheel and chain may move together, they may under certain conditions have independent movements, the wheel 100 merely forming a support for the chain.

Accordingly, if, for any reason, the wheel should become caught, the mechanism would not thereby be impaired, for the chain would move on the wheel and the operation of the mechanism be completed.

5 An opening 5^a, provided near the periphery of the wheel in one of the walls of the groove, permits the passage of links and pins to enable assembling and disassembling 10 of the chain upon the wheel and facilitates the repair of the chain.

15 A bracket or standard 7 is mounted upon the shelf 2^b, and supports the ends of shafts 8 and 12, the opposite ends of these shafts 20 being journaled in the plate 2^a. The shaft 8 carries intermediate its ends a sprocket wheel 9, which is so placed as to engage the sprocket chain 6. At one end of the shaft 8 is a gear 10 which meshes with the gear 11 25 carried upon a shaft 12. Upon the opposite end of the shaft 12 is a gear 13 which, in turn, meshes with a gear 14 carried upon the shaft of a motor 15. It will be apparent that as the motor is operated, the gears 14, 30 13, 11 and 10, and the sprocket wheel 9, will be driven, which will thereby cause the movement of the sprocket chain 6.

35 A bent lever 16 is mounted near its central portion upon the shaft 4. This lever 30 (which, by mechanism to be hereinafter described, operates the semaphore arm) is composed of two parts which straddle the wheel 5 and are secured together at their outer ends by means of a pin 17, and a pin 35 31^b, for the latch 31, to be later described. Upon the shaft 4 is pivoted an arm 18 which is likewise secured to the pin 17, and moves in unison with the lever 16. A shaft 19 is suitably mounted beneath the mechanism 40 previously described and upon its end is a crank arm 20 which, at its free end, is pivotally connected with a rod 21, which, in turn, is pivotally secured at substantially the central portion of the member 18.

45 At a point near the track an upright shaft 22 is mounted upon which is secured a contact arm 23, which normally projects toward the track. Upon the shaft 22 is a bevel gear 22^a, which meshes with a bevel 50 gear 19^a, the last mentioned gear being secured upon the shaft 19. The gears 22^a and 19^a, as well as a portion of the shaft 22, may be secured within a suitable housing 22^b, which will protect the elements just 55 mentioned from wear and tear incident to their use and also provide a suitable means for mounting the shaft 22. It will be apparent, however, that other connections may be employed between the rod 21 and the arm 23 without in any way departing from the 60 spirit of the invention.

65 As shown in Fig. 1, the arm 23 projects in the path of travel of a lever 24 which is pivotally carried upon the locomotive and 65 may be operatively connected with the air

line for the brakes upon the train or may operate a cab signal or accomplish both of these or other results.

Upon the opposite end of the lever 16 from that already described, a sprocket 70 wheel 25 is mounted which engages with the sprocket chain 6. This sprocket wheel is rigid upon a shaft journaled in the two side pieces of the lever 16, and upon this shaft is a notched disk 26. The lever 16 also 75 carries an electromagnet 27 and a pivoted armature 28 therefor. The armature 28 is provided with an elongated arm 29, which has a tooth 30 so positioned that it may engage with one of the notches of the disk 26 80 when the armature 28 is acted upon by the magnet. This structure I term a magnetic latch.

85 The lever 16, at its extreme end, is provided with a latch 31 which is weighted at the upper portion thereof, 31^a, so as to normally throw the toe of the latch in an outward direction. Upon a suitable support 33, carried by the plate 2^a, is pivoted a lever 34, which is provided with a weighted portion 35, normally tending to throw the lever proper 34 away from its vertical position. The upwardly extending arm 34^a of this lever is adapted to be engaged at certain times by a latching arm 36. This latching 95 arm is pivoted upon an upright portion 33^a of the support 33; it is weighted at its rear portion so that it normally stands out of engagement with the arm 34^a. This latching arm acts as the armature for an electromagnet 37, the operation of which will be later 100 described.

40 designates the semaphore blade, which is pivoted at the top of the tower and connected with the up-and-down rod 39 in such 105 manner (well known in this art) that when the rod is shoved upward the blade swings downward or into safety position, while when the rod descends it returns the blade to its horizontal or danger position. On the 110 lower end of the rod 39 is a head 39^a from which depends a rod 39^b connected at its lower end, by a loose play connection, with the lever 16.

An arm 39^c is carried by the head 39^a and 115 extends downwardly and at its lower end is provided with a hook 39^d. The lever 16 likewise carries an arm 16^a which is provided with a hook 16^b. The arms 16^a and 39^c are so mounted that when the parts of the 120 mechanism are in the position shown in Fig. 3, the hooks 16^b and 39^d will be in engagement, thereby locking the rod 39 in its down position. When the lever 16 is moved from the normal position shown in Fig. 3, 125 by the operation of the device, the hook 16^b releases the hook 39^d so that the rod 39 may be raised. The loose play between the pin 16^c on the lever 16 and the top of the slot in the rod 39^b, allows sufficient idle movement 130

of the lever 16 to cause the hooks 16^b and 39^a to unlatch before the rod 39^b is engaged and shoved upwardly. The rod 39 cannot operate the lever, due to the lock and the loose play below the pin 16^c.

5 The normal locking of the rod 39 against upward movement, as described, is an important feature, as it positively locks the semaphore blade in danger position and 10 prevents its accidental displacement by external forces, such, for instance, as the accumulation of ice or snow on the semaphore blade, which in the past has sometimes caused the blade to droop, thereby wrongly 15 indicating safety.

A suitable dash pot is provided for use in connection with the rod 39 for securing a steady and slow return of the rod to its normal position. As here shown, the arm 20 3^a of the bracket 3 carries the dash pot cup 41 in which is a piston 42, the piston being connected with the head 39^a, by means of a link 43, which is pivoted thereto.

A knife switch 45 is mounted upon an insulating block 44 which is upon the arm 3^b 25 of the bracket 3. This switch comprises a comparatively long arm 45^a and a shorter arm 45^b. The arm 45^b is one terminal of an electric line and adapted to coöperate with 30 a stationary terminal 46, which is also carried upon the block 44. A spring 47 is connected with the arm 45^b and with the block upon which it is mounted, in a manner to 35 throw the switch completely in one direction or the other. That is to say, if the arm 45^b be removed out of engagement with the terminal 46, the spring will tend to carry it entirely away from such terminal, whereas, if the arm 45^b be moved into contact with the 40 terminal 46, the spring will tend to hold it in such engagement.

The arm 45^a extends in a path of travel of two stops, 48 and 49, which are upon the rod 39^b so that, when this rod is raised, the 45 stop 49 will engage with the lever 45^a and rock the same to cause the disengagement of the arm 45^b with its companion terminal 46, and when the rod 39^b descends, the arm 45^a 50 will be engaged by the stop 48 to close the switch, as indicated in Fig. 3.

The relay 1 is provided with an armature 1^a, which is electrically connected with the battery B, or other source of electric power, by means of a conductor c. The battery is 55 also connected with one of the poles of the motor 15 by means of a conductor d, and the other pole of the motor is connected with the stationary terminal 46 of the switch by a conductor e. A conductor f connects the 60 conductor d with one of the poles of the electromagnet 27, the other pole of this electromagnet being connected with the switch terminal 46 by means of a conductor g. The arm 45^b of the switch is connected with a 65 conductor h, and when the armature 1^a is

closed, the conductors h and c become connected, closing battery circuits in parallel through the motor and the magnet 27 of the magnetic latch.

A conductor j connects one pole of the 70 electromagnet 37 with the conductor f, and the other pole of this electromagnet is connected by a conductor k with the conductor h. This magnet accordingly is in a shunt around the motor and switch and the magnetic latch and switch. 75

From the foregoing description, it will be seen that when the relay 1 is energized and its armature is raised, an electric current passes from the source of electrical energy B through the conductor d, motor 15, conductor e, terminal 46, switch arm 45^b, conductor h, conductor c, and thence to the battery. This will operate the motor and cause the rotation of the sprocket chain 6. 35 Simultaneously, a portion of the current passing over the conductor d will pass over the conductor f, through the electromagnet 27, and via the conductor g, the switch and conductors h and c to the battery. This 40 will cause the armature 28 of the magnetic latch to be drawn toward the magnet causing the detent 30 to engage with one of the notches in the disk 26. This will prevent rotation of the sprocket wheel 25 and will 45 thereby lock it to the chain 6, causing the sprocket wheel and the end of the lever upon which it is mounted to be raised by the continued travel of the chain. This, in turn, will cause the rod 39^b to be pushed upward and thereby will raise the rod 39 and cause the semaphore to assume a depending or safety position. This same operation causes the rod 21 to be pushed down, which 50 rocks the shaft 19, and, through the intermediary of the gears 19^a and 22^a, rotates the shaft 22 and turns the arm 23 into a position parallel with the track so that the signal lever carried by the locomotive will not 55 be engaged by the arm 23. The current 100 which passes over the conductor f will divide and a portion thereof will pass over the conductor j, through the electromagnet 37, and the conductors k, h and c, to the battery. This will cause the armature 36 to be 105 60 pulled down and engage with the arm 34^a of the latch 34. When the end of the lever 16 reaches a certain elevation, the stop 49 engages with the switch arm 45^a and separates the switch member 45 from the member 46. This operation opens the circuit 110 through the motor, as well as the circuit through the electromagnet 27, so that the armature 28 drops and releases the sprocket wheel 25, permitting the same to rotate upon 115 its shaft. The tendency now is for the lever 16 to drop, but the latch 34 will engage with the latch 34 and hold the lever 16 in elevated position so long as the magnet 37 is 120 energized.

It will be understood that the motor cannot be stopped immediately by simply ceasing the supply of the current, for the momentum will cause it to rotate for a short time, after the current has ceased. This, therefore, will cause the wheel 5 to continue its rotation for a period, after the motor has ceased to be energized. However, inasmuch as the sprocket wheel 25 has become free to rotate because of the deenergization of the electromagnet 27, the lever 16 will not be moved farther and the wheel 5 will simply turn idly until it comes to rest, and prevent any jamming of the motor. However, the lever 16 cannot return to its normal position immediately, because of the engagement of the latch 31 with the catch 34, and will be held in its elevated position until such time as the relay 1 becomes deenergized. At that time the armature 1^a drops and opens the circuit and deenergizes the electromagnet 37, whereupon the latching arm 36 rises and the weight of the rod 39, which is supported from the lever 16 upon the catch 34, causes the latter to move about its pivot, thereby releasing the latch 31. The rod 39 will then be free to return to its initial position, but its return will be gradual and under control of the dash pot. The arm 29 of the armature 28 is made long so that it will mechanically engage with the knock-out bolt 29^a upon the bracket 3 and thereby release the toothed disk 26 and the sprocket wheel 25 in the event that the switch 45 should fail to operate, as for example, by the current arcing its separated terminals.

The whole mechanism, just described, is usually protected by a housing, represented at D in Fig. 1, and the shaft 19 extends from the housing D to the point at which it is desired to mount the arm 23.

Having thus described my invention, what I claim is:—

- 45 1. The combination of a driving chain, a wheel loosely carrying said chain about its periphery, a rotatable bodily movable device coöperating therewith, means for controlling the rotation of said device whereby it may be either turned on its axis or be moved bodily by the driver, a signal, and a connection between the same and said device, whereby the movement of the latter may operate the signal.
- 50 2. The combination, with a motor, of an endless chain, a circular support therefor, a lever pivoted at the axis of said support, a rotatable member upon said lever engaging with the chain, means for holding said member against rotation, whereby the lever will be operated as the motor is energized, means for automatically releasing the member when the lever is at a predetermined position, whereby the member may turn idly

upon the lever as the lever returns to normal position. 65

3. The combination with a motor, of a rotatable member operatively connected therewith, a pivoted lever, a wheel upon the lever adapted to contact with said rotatable member, a latch carried by the lever adapted to hold the wheel against rotation, whereby the lever may be moved as the motor is operated, and means for unlatching the wheel whereby it may run idly upon the rotatable member, and means for holding the lever in its moved position. 70 75

4. The combination with a rotatable member mounted upon an axis, of a lever pivoted upon the axis of the rotatable member, means carried upon the lever engaging with the rotatable member, a latch for preventing independent movement of said means, whereby the lever will be moved as the rotatable member is moved, and means for disconnecting the latch after the lever has moved a predetermined distance. 80 85

5. The combination with a rotatable member mounted upon an axis, of a two part lever straddling said rotatable member, means carried at one end of the lever engaging with the rotatable member, a latch for holding said means against movement, and means for disconnecting the latch after the lever has moved a predetermined distance. 90 95

6. The combination of a driving member consisting of a wheel carrying loosely about its entire periphery an endless freely movable driver, a rotatable bodily-movable device coöperating therewith, means carrying said device and pivoted on the same axis with the wheel, means for controlling the rotation of said device, whereby it may either turn on its axis or be moved bodily by the driver, means for holding said device in a position into which it has bodily traveled, and a signal operated by such travel. 100 105

7. The combination with a driver, a rotatable bodily-movable member connected therewith, an electromagnetic latch for holding the rotating member against rotation, an electric circuit of which the said magnetic latch is a part, a lever carrying said rotatable member, means for opening said circuit when the lever reaches a predetermined position, whereby the magnetic latch will be deenergized, and means for holding the lever in its operated position. 110 115

8. The combination with a motor, of a device driven thereby in a vertical plane, a lever, a rotating member carried by said lever and engaging with said device, an electromagnetic latch carried by the said lever and adapted to hold the rotating member against rotation, whereby the rotating member will be raised bodily, an electric circuit controlling the motor, a second electric circuit con- 120 125

trolling the magnetic latch, means for opening the circuits before mentioned when the lever reaches a predetermined position, a detent adapted to hold said lever in its elevated position, an electromagnet controlling said detent, and means controlling the electric circuit of which the last mentioned electromagnet is a part.

9. The combination of a rotatable wheel, 10 a driving sprocket chain loose in a circular course about the periphery thereof, a rotatable sprocket wheel engaging such chain, a signal and connection between the same and the sprocket wheel.

10. The combination of a rotatable wheel, 15 a driving sprocket chain embracing the periphery thereof but loose thereon, a rotatable sprocket wheel engaging such chain, a signal, a connection between the same and the sprocket wheel whereby the signal may be thrown by the travel of the sprocket wheel bodily, and means for preventing the rotation of the sprocket wheel, thereby causing it to travel bodily.

11. The combination with an annular member mounted upon an axis, said annular member having a groove in the periphery thereof, a sprocket chain encircling the said member within the said groove, a bodily 30 movable sprocket wheel engaging with the said chain, means for holding said sprocket wheel against rotation, whereby it will be shifted as the chain is moved, and means for disconnecting the holding means after 35 the wheel has been shifted a predetermined amount, whereby the sprocket wheel may run idly upon the chain.

12. The combination with a rotatable wheel having a groove in the periphery 40 thereof, of a sprocket chain encircling the said member and loose within the said groove, a bodily movable sprocket wheel engaging with said chain, means for holding said sprocket wheel against rotation, and a signal operated by the body movement of said wheel when so held.

13. The combination with an annular member, of an axis upon which said member is rotatably mounted, a sprocket chain 50 carried by said annular member upon the periphery thereof, a sprocket wheel meshing with said chain, means for driving the sprocket chain, a lever pivoted upon the same axis as the annular member, a sprocket 55 wheel carried by said lever and meshing with the chain, a notched member connected with the sprocket wheel upon the lever, a pivoted detent upon the lever adapted to engage with the said notched member, 60 whereby the sprocket wheel will be held against rotation and the lever will be moved as the chain is operated, means for releasing the detent after the lever has moved a predetermined distance, a latch adapted to

engage the lever in its raised position, and 65 means for operating said latch to release the lever.

14. The combination, with a semaphore signal, of a rod for operating said signal, 70 a lever for raising and lowering the rod, co-operating members carried by the lever and the rod for locking the two together when the rod is in an extreme position, and means for operating the lever.

15. The combination, with a semaphore 75 signal, of a rod operatively connected to said signal, a lever with which said rod is connected for raising and lowering the said rod, a hook connected with said rod and a co-operating hook connected with said 80 lever, said hooks engaging each other when the rod is in its lowermost position, and means for operating the lever first to release the hooks and then raise the rod.

16. In a mechanism of the class described, 85 the combination of a rotatable wheel, an endless chain loose on the periphery thereof, a lever pivoted concentric of the wheel, a pinion carried by the lever and adapted to co-operate with the chain, means for locking 90 or releasing the pinion, and mechanism operated by the movement of the lever.

17. In a device of the character described, the combination of a rotatable wheel having 95 a grooved periphery, a sprocket chain loosely mounted in said periphery, a device movable concentrically of the sprocket chain, a rotatable pinion carried by the device and engaging the chain, means for holding the pinion against rotation or allowing it to rotate, and mechanism operated 100 by the movement of said device.

18. In a device of the character described, the combination of a rotatable wheel having 105 a grooved periphery, an endless traveling chain loosely mounted on said periphery, a device movable concentrically with the chain, a pinion mounted so as to be rotatable adjacent to said periphery and bodily movable with said device, said pinion meshing 110 with the chain, means for holding the pinion against rotation to compel its movement by the chain bodily or for releasing it to allow it to rotate on its axis, and mechanism operated by the movement bodily of the 115 pinion.

19. The combination of a wheel mounted to turn on its axis, an endless member loosely mounted on the periphery thereof, a motor geared with said endless member, an 120 arm pivoted concentrically of the wheel, a device carried by the arm and adapted to be locked to the endless member, and mechanism connected with the arm.

20. The combination of a rotatable wheel, 125 a chain loosely mounted on the periphery of the wheel, a motor geared with the chain, an arm pivoted concentrically of the wheel,

a device carried by the arm and adapted to engage the chain and lock the arm thereto, and mechanism connected with the arm.

21. The combination of a rotatable wheel having an annular groove in its periphery, an endless chain seating in said groove and adapted to move independently of the wheel, a driving device geared with said chain, an arm pivotally mounted on the axis of the wheel and extending to the periphery there-

of, a device carried by said arm for locking the arm to the chain, and mechanism operated by the movement of said arm.

In testimony whereof, I hereunto affix my signature in the presence of two witnesses. 15
